UNITED STATES PATENT OFFICE.

JAMES A. WOTTON, OF MONTCLAIR, NEW JERSEY, ASSIGNOR TO WESTERN ELECTRIC COMPANY, OF NEW YORK, N. Y., A CORPORATION OF ILLINOIS.

SELECTIVE IMPULSE-TRANSMITTER.

1,100,413.

Specification of Letters Patent. Patented June 16, 1914.

Application filed February 8, 1912. Serial No. 676,277.

To all whom it may concern:

Be it known that I, JAMES A. WOTTON, citizen of the United States, residing at Montclair, in the county of Essex and State of New Jersey, have invented a certain new and useful Improvement in Selective Impulse-Transmitters, of which the following is a full, clear, concise, and exact description.

This invention relates to impulse controlling means for selective signaling or like systems and has for its object to provide current impulse controlling means for the above purpose which may be readily and accurately manipulated by the calling party. 10 In accordance with this invention this is accomplished by providing in combination with an impulse transmitter, a controlling mechanism comprising a movable member carrying contact controlling means operating in conjunction with key plungers to determine the number of current impulses.

In the preferred form of the invention the movable member comprises a rotating shaft upon which is mounted a plurality of cam disks, the shaft being supported in a frame carrying a plurality of plungers corresponding to the number of cam disks on the shaft. Spring contacts under the joint control of any plunger and its corresponding cam disk 25 are closed at a particular point in the rotation of the shaft when that plunger is depressed and thus determine the number of impulses sent out on the receiving circuit by the impulse transmitter.

Specific features of the invention lie in the details of construction for automatically releasing the last plunger depressed; for causing a first preliminary long impulse of current when the mechanism is started, for 30 automatically causing the operation of the shaft when a plunger is depressed and for causing said shaft to complete one revolution after started.

In the drawings illustrating this invention, Figure 1 is a plan view of the mechanism with parts broken away. Figs. 2, 3, 4 and 5 are detail sectional views taken upon lines 2-2, 3-3, 4-4 and 5-5 of Fig. 1 and Fig. 6 is a detail view of the apparatus and 45 circuits.

Referring to the drawings, 5 designates a shaft rotatably supported at its ends in frame members 6 and 7. Mounted upon one

end of this shaft 5 outside the frame member 6 is a ratchet wheel, 8 adapted to be engaged by a stepping pawl, 9 carried by the armature 10 of a motor magnet 11. Mounted upon the frame member 6 adjacent, the ratchet wheel 8 is a spring pressed holding pawl 12. Carried by the shaft 5 are a plurality of cam disks 15, 15 preferably of metal and each provided with a notched or cut-away portion 16. The disks 15, 15 are all the same in construction but are secured to the shaft with the notches 16 in staggered relation, the difference in position of the notches of adjacent disks being the distance the shaft 5 will be advanced by one step of the motor magnet.

Located adjacent to each of said cam disks 15, 15 is a plunger member 20 having its opposite ends supported in side frame members 21 and 22. Each plunger is surrounded near its inner end with a coiled spring 23 tending normally to push the plunger outwardly. Secured to a shelf 24 mounted upon the front frame member 21 are a plurality of spring contact members 25, 25 one for each plunger 20. Each of said springs 25, 25 is provided at its free end with a finger portion 26 normally in engagement with the corresponding plunger 20 and with a notched portion 27 adapted to engage the periphery of the adjacent cam disk 15. Each plunger 20 is provided with a plurality of notches 30, 31 and 32. The notch 30 is adapted when the plunger 20 is depressed to receive the finger portion 26 of the spring 25, which permits the notched portion 27 of said spring to drop into engagement with the periphery of the adjacent disk 15. A locking bar 35 normally in engagement with the notch 31 is brought into engagement with the notch 32 by the operation of the key plunger. Located adjacent to said notch 32 and pivotally supported upon the plunger 20 is a trigger finger 36 adapted in the rotation of the cam 15, to be engaged by a projecting trip member 37 carried by said cam to release the locking bar and permit the plunger 20 to return to normal position.

Located beneath the springs 25 and adapted to be engaged by one of the said springs when the notched portion 27 of the corresponding cam disk 15 is a contact bar 40. Located at the back of the structure in

position to be engaged by the inner ends of the plungers 20, 20 is a pivotally supported plate 45 adapted when actuated by one of said plungers 20 to close contact between two sets of contact springs 46 and 47 for the purpose hereinafter set forth.

Mounted near one end of the shaft 5 adjacent to the motor magnet 11 is a cam disk 50 controlling a set of contact springs 51. In the normal position of the parts the lower one of these springs is in engagement with a notch 52 in the disk 50 and the contacts are open. As the shaft begins to rotate, however, the contact is closed and remains so until the disk 50 has been turned through one revolution. These springs control the circuit of the motor magnet 11. Upon the opposite end of the shaft 5 is a disk 55 having a raised portion 56 thereon adapted to engage and close contact between a set of springs 57 for the purpose hereinafter set forth. Each key plunger is provided on its outer end with an index button 60 to designate the number of the station on the line which will respond to the operation of the particular key.

The operation of the apparatus and circuits may be best followed by reference to Fig. 6 and is as follows. Assuming that the parts are in the position shown in Fig. 6 with the contacts 57 closed and those at 51 open and it is desired to signal the party whose selector operates in response to the operation of key index 25. When this key is operated the plunger 20 is moved into position to permit the finger portion 26 of the spring 25 to drop into the notch 30 and bring the notch 32 into engagement with the latch plate 35. In this position the plunger 20 closes the contacts 46 and 47, and maintains them closed until said plunger is released. The closure of the contacts 47 completes two circuits, one of which is through a vibrator 65, the other being through an impulse transmitter 66 and the motor magnet 11 in series. The first of these circuits may be traced from one side of a battery 67, over conductors 68 and 69, winding of vibrator 65, an operating contact 70 thereof, conductor 71, contacts 47, conductor 72, to the other side of the battery 67. Current in this path causes the operation of the vibrator to cause the alternate opening and closing of the contacts 70 and 75 of the vibrator. The other circuit closed by the contacts 47 may be traced from one side of battery 67 over conductor 68, conductor 76, winding of impulse transmitter 66, conductor 77, winding of motor magnet 11, conductor 78, contacts 75 of the vibrator 65, conductor 79, conductor 71, contacts 47, conductor 72, to the other side of battery 67. This last circuit is alternately opened and closed at contacts 75 by the operation of the vibrator and at each closure thereof causes

the attraction of the armature 10 of the motor magnet 11 and also a closure of a contact 80 of the impulse transmitter 66. Each attraction of the armature 10 of the motor magnet operates through the pawl 9 and ratchet 8 to advance the shaft 5 one step. The contact 80 of the impulse transmitter 66 is for the purpose of sending current impulses out on the line wires 85 and 86, but is ineffective for this purpose during the first few preliminary steps of the shaft 5 inasmuch as the closure of the contacts 46 and 57 has established a circuit for battery 87 which may be traced as follows: from one side of battery 87 conductor 88, contacts 46, conductor 89, line wire 85, through selector bridge 90, line wire 86, conductor 91, contacts 57, conductor 92, conductor 93 to the other pole of said battery. So long, therefore, as the contacts 57 are closed, there will be a steady flow of current to the line wires which is in the nature of a long impulse. As soon, however, as the shaft 5 has been rotated a sufficient distance to move the projection 56 away from these springs 57 to open the last traced circuit, the opening and closing of the contact 80 will control a circuit of the battery 87 which may be traced as follows: from one side of battery 87, conductor 88, contact 46, conductor 89, line wire 85, selector bridge 90, line wire 86, conductor 94, contact 80 and conductor 95 to the other pole of the battery 87. These impulses will continue between the time of the opening of the contacts 57 and the time that the reduced portion 27 of the spring 25 drops into the notch 16 of the disk 15. When this occurs, the spring 25 will be dropped into contact with the bar 40 and will complete a circuit for battery to line similar to that traced through the contacts 57 except that the contacts 25 and 40 will be substituted for contacts 57. This will short-circuit the impulse transmitter contacts and maintain current upon the line for a considerable period of time which may be termed the ringing period. The length of this period is the time required for the notched portion 16 of the disk 15 to pass under the spring 25 and to again lift it from engagement with the bar 40. Shortly after the contact between the spring 25 and the bar 40 has been opened, the tripping finger 37 will be brought into engagement with the trigger finger 36 operating it to raise the latch plate 35 and release the plunger 20 permitting it to return to normal position and opening the contacts 46 and 47. The motor magnet 11 will continue operating, however, because of the fact that after the first few preliminary steps the contacts 51 were closed by the cam 50 and as these contacts are in multiple with the contacts 47, the operating circuit of the motor magnet will be closed until the cam 50 has rotated into position to

permit the lower spring 51 to drop into the notch 52, thereby opening these contacts.

I claim:—

1. The combination with an impulse transmitter and an impulse receiving circuit, of a plunger member, a shaft adapted to rotate and to make one complete revolution upon the actuation of said plunger member, means to prevent rotation of said shaft in reverse direction, and means under the joint control of said plunger member and said shaft for controlling the number of impulses sent over said circuit by said impulse transmitter in one revolution of said shaft.
2. The combination with an impulse transmitter and an impulse receiving circuit, of a rotating shaft, means for synchronizing the operation of said shaft and said impulse transmitter, a plunger member, means under the joint control of said plunger member and said rotating shaft for determining the number and character of the impulses sent over said receiving circuit in one revolution of said shaft, and means to prevent rotation of said shaft in reverse direction.
3. The combination with an impulse transmitter and an impulse receiving circuit, of a plunger member, a shaft adapted to rotate, to make one complete cycle and to operate in unison with said impulse transmitter upon the actuation of said plunger member, means under the joint control of said shaft and said plunger member for determining the number and character of the impulses sent over said receiving circuit in one revolution of said shaft, and means to prevent rotation of said shaft in reverse direction.
4. The combination with an impulse transmitter and an impulse receiving circuit, of a rotating shaft, a plunger member, circuit closing means controlled by said shaft for sending a preliminary impulse of a given character over said receiving circuit, and circuit closing means under the joint control of said plunger and said rotating shaft for determining the number and character of the succeeding impulses sent over said receiving circuit.
5. The combination with an impulse transmitter, and an impulse receiving circuit, of a rotating shaft operating in unison with said impulse transmitter, a plunger member controlling the operation of said shaft and said impulse transmitter, contacts controlled by said shaft for sending a preliminary impulse of given character over said receiving circuit, and means under the joint control of said plunger member and said rotating shaft for determining the number and character of the succeeding impulses sent over said receiving circuit.
6. Impulse controlling means comprising in combination an impulse transmitter, contact members operating in conjunction therewith, a rotatable shaft, a cam disk car-

ried thereby, and a plunger member, the engagement of said contact members being under the joint control of said cam disk and said plunger member.

7. Impulse controlling means comprising in combination a contact spring and bar normally out of engagement with each other, an impulse transmitter operated in conjunction with said spring and bar, a rotatable shaft, a cam disk thereon, having a cutaway portion, and a plunger member upon which one end of said spring normally rests, but having a cut away portion adapted when said plunger member is operated to permit said spring to engage the periphery of said cam disk and the spring to engage said bar when the cut-away portion of said disk is brought under said spring.

8. Impulse controlling means comprising in combination an impulse transmitter, a rotating shaft, means for synchronizing the operation of said shaft and said impulse transmitter, a cam disk carried thereby, a plunger member, a latch member for holding said plunger in operated position, a spring contact operating in conjunction with said impulse transmitter under the joint control of said cam disk and said plunger member, and means operated in the rotation of said shaft for releasing said latch member.

9. Impulse controlling means comprising in combination a rotating shaft, a cam disk carried thereby, a plunger member provided with a notch, a latch plate adapted to engage said notch when said plunger is operated, a trigger finger, means on said cam disk adapted in the rotation of said shaft to engage said trigger finger to raise said latch plate, contact springs under the joint control of said cam disk and said plunger, an impulse transmitter operating in conjunction with said springs, and means for synchronizing the operation of said shaft and said impulse transmitter.

10. Impulse controlling means comprising in combination a rotatable shaft, a driving motor therefor, a plurality of cam disks mounted upon said shaft, a corresponding number of plunger members, a spring contact under the joint control of each of said cam disks and the corresponding plunger, an impulse transmitter operating in conjunction with each of said spring contacts, and an operating circuit for said motor magnet initially under the control of any one of said plunger members.

11. Impulse controlling means comprising in combination a rotatable shaft, a driving motor therefor, a plurality of cam disks mounted upon said shaft, a corresponding number of plungers, a spring contact under the joint control of each of said cam disks and the corresponding plunger, an impulse transmitter operating in conjunction with said spring contacts, a swinging plate oper-

- ated by any one of said plungers, and spring contacts controlled by the operation of said swinging plate.
12. Impulse controlling means comprising in combination a rotatable shaft, a driving motor therefor, adapted when operated to turn said shaft through one complete revolution, a plurality of cam disks carried by said shaft, a corresponding number of plungers, 5
10. a spring contact under the joint control of each of said cam disks and a corresponding plunger, an impulse transmitter operating in conjunction with each of said spring contacts, means for holding said plunger in its operated position, releasing means therefor, operated in the rotation of said shaft, an operating circuit for said magnet under initial control of any one of said plungers, and means operated by said shaft for continuing 20
25. said circuit after the release of the plunger and until the completion of the revolution of said shaft.
13. The combination with line wires, of a source of current, an impulse transmitter for intermittently connecting said source of current with said line wires, a rotating shaft, a motor magnet for said shaft, means for operating said motor magnet and said impulse transmitter in unison, means under 30
35. control of said shaft for preventing the preliminary operation of said transmitter from sending out impulses, and means also under control of said shaft for determining the number of impulses sent out in the operation of said impulse transmitter.
14. The combination with line wires, of a source of current, an impulse transmitter for intermittently connecting said source of current with the line wires, a rotating shaft, 40
45. a motor magnet for said shaft, means for operating said motor magnet and impulse transmitter in unison, contacts controlled by said shaft for maintaining a preliminary long impulse of current upon the line and contacts also controlled by said shaft for applying continuous current to the line wires after the requisite number of impulses have been sent.
15. The combination with line wires, of a source of current, an impulse transmitter, 50
55. contacts controlled thereby for intermittently connecting said source of current with said line wires, a rotating shaft carrying cam disks, a motor magnet for operating said shaft, a vibrator for operating said motor magnet and said impulse transmitter in unison, a plunger, a circuit for said vibrator closed by the operation of said plunger, contacts controlled by one of the disks upon 60
65. said shaft for short circuiting the contacts of said impulse transmitter during a preliminary movement of said shaft, and contacts controlled jointly by said plunger and another cam disk upon said shaft for short circuiting the impulse transmitter contacts
- after the requisite number of current impulses have been sent.
16. Impulse controlling means comprising in combination with an impulse transmitter, a movable member adapted to move 70
75. in one direction, means for synchronizing the operation of said movable member and said impulse transmitter, means to prevent movement of said member in reverse direction, contact controlling devices carried by said movable member, plungers, and means under the joint control of said contact controlling devices and said plungers for controlling the number of impulses sent out by said transmitter.
17. Impulse controlling means comprising in combination with an impulse transmitter, a movable member, means for synchronizing the operation of said movable member and said impulse transmitter, contact controlling cam disks carried by said member, a corresponding number of plungers, and contact springs under the joint control of any one of said cam disks and its corresponding plunger for controlling the 80
85. number of impulses sent out by said transmitter.
18. The combination of an impulse transmitter and an impulse receiving circuit, of a plunger member, a rotatable shaft, contacts controlled by the depression of said plunger member for sending a preliminary impulse over said circuit, a cam disk carried by said shaft, and contacts under the control of said cam disk for determining 90
95. the number of succeeding impulses sent over said circuit by said impulse transmitter.
19. The combination of an impulse transmitter and an impulse receiving circuit, of a plunger, a rotatable shaft initially under 100
105. the control of said plunger, spring contacts closed by the depression of said plunger for sending a preliminary impulse over said circuit, a cam disk carried by said shaft, and contacts under the control of said cam disk for determining the number of succeeding 110
115. impulses sent over said circuit by said impulse transmitter.
20. The combination with line wires, of a source of current, an impulse transmitter for intermittently connecting said source of current with said line wires, a rotating shaft, means for operating said shaft and said impulse transmitter in unison, a plurality of cam disks carried by said shaft, and contacts under the control of said cam disks for determining the number and character of impulses sent out by the operation of said impulse transmitter.
21. The combination of line wires, of a source of current, an impulse transmitter for intermittently connecting said source of current with said line wires, a rotating shaft, a vibrator for operating said shaft and said impulse transmitter in unison, con- 120
- 125
- 130

tacts under the control of said shaft for sending out a preliminary long impulse and for preventing the preliminary operation of said impulse transmitter from sending out 5 short impulses, a plurality of cam disks carried by said shaft, and contacts under the control of said cam disks for determining the number of succeeding short impulses

sent out by the operation of said impulse transmitter.

In witness whereof, I hereunto subscribe my name this sixth day of Feb. A. D. 1912.

JAMES A. WOTTON.
